[57] CLAIM

The ornamental design for a diary, as shown and described.

DESCRIPTION

FIG. 1 is a perspective view of the diary in a closed condition showing our new design;

FIG. 2 is a front end plan view thereof;

FIG. 3 is a top plan view thereof;

FIG. 4 is a bottom plan view thereof;

FIG. 5 is a rear end plan view thereof;

FIG. 6 is a perspective view of the diary in the unlocked open condition;

FIG. 7 is a front end plan view of FIG. 6;

FIG. 8 is a top plan view of FIG. 6; the bottom plan is identical to the top plan view; and

FIG. 9 is a rear end plan view thereof.
